UNITED STATES PATENT OFFICE

156,303

DESIGN FOR A MANICURE TRAY

James W. Wheeler, Cincinnati, Ohio

Application October 11, 1948, Serial No. 149,072

Term of patent 7 years

(Cl. D86—10)

To all whom it may concern:

Be it known that I, James W. Wheeler, a citizen of the United States, residing at Cincinnati, in the county of Hamilton and State of Ohio, have invented a new, original, and ornamental Design for a Manicure Tray, of which the following is a specification, reference being had to the accompanying drawing, forming part thereof.

Figure 1 is a top plan view of a manicure tray, showing my new design;

Figure 2 is a side perspective view thereof;

Figure 3 is a further perspective view taken substantially at right angles to that in Figure 2, and

Figure 4 is a further perspective view taken in a direction opposite to that in Figure 2.

I claim:

The ornamental design for a manicure tray, as shown.

JAMES W. WHEELER.
